FIG. 1.

FIG. 2.

FIG. 3.

FIG. 4.

FIG. 5.

FIG. 6.

FIG. 1 is a top plan view of a molded packaging tray for meat showing our new design;

FIG. 2 is a front elevation view, partly broken away at the right hand side, of the tray of FIG. 1; and

FIG. 3 is a side elevation view of the tray of FIG. 1.

FIG. 4 is a view similar to FIG. 1 but showing a modified form of our new design;

FIG. 5 is a front elevation view, partly broken away at the right, showing the tray of FIG. 4; and

FIG. 6 is a side elevation view of the tray of FIG. 4.

The characteristic feature of the design resides in the inverted V-shaped ribs forming a bottom of hexagonal shaped open windows at the central portion with other polygonal windows around the periphery, as shown.

We claim:

The ornamental design for a molded packaging tray for meat or the like, as shown and described.
